UNITED STATES PATENT OFFICE.

CLYDE P. ROSS, OF CHICAGO, ILLINOIS.

DRIER.

Application filed December 12, 1925. Serial No. 74,965.

This invention relates to a drier and particularly to an apparatus for drying material such as sand and small gravel, although it is not limited to use on such material. 5 The form shown herewith is particularly adapted to dry sand. One object of the invention is to provide a compact and durable apparatus for drying sand and to embody in such an apparatus means for drying the sand rapidly. Another object is to embody in such an apparatus means for heating the sand throughout its mass. Another object is to provide means for vibrating and shaking the mass of sand during the time of 10 drying. Other objects will appear from time to time throughout the specification and claims.

My invention is illustrated more or less diagrammatically in the accompanying 20 drawings, wherein:

Figure 1 is a partial plan view with parts omitted;

Figure 2 is a vertical section taken on line 2—2 of Figure 1;

25 Figure 3 is a transverse vertical section taken on line 3—3 of Figure 2;

Figure 4 is a horizontal section taken on line 4—4 of Figure 2.

Like parts are indicated by like characters 30 throughout.

The drier proper is formed of a coil of pipe consisting of a coil portion A which flares outward as it extends upward, and to which steam or other heating fluid is supplied 35 through a pipe A¹ which is controlled by a valve A². At its bottom a discharge connection A³ is provided with a valve A⁴. As shown herewith the coil portion A is generally rectangular in plan, and it is further 40 provided with a central heating section B. This is formed of a pipe which is bent or looped back and forth as best shown in Figure 2. This central heating element is joined to the supply pipe A¹ at the connection B¹ and it is joined to the discharge pipe A³ at the connection B².

45 C C are stiffening elements fastened to the central heating element B serving to give it strength and rigidity.

50 D D are stiffening or frame elements lo-

cated at appropriate intervals along the sides of the main coil portion A. Portions of them are joined at their bottoms by bolts D¹. They terminate at their tops preferably in hanger portions D² by means of which the entire heater may be supported from above.

E E are hangers attached preferably one to each end of a loop of the central heating element B and each hooked over a portion 60 of the coil A.

F F are intermediate stiffening and strengthening means attached to the coil A, located preferably one on each side of the drier between the stiffening members D. 65 The members F do not terminate in hangers or other parts extending above the drier.

G G are bottom portions preferably made stationary within the bottom of the drier. G¹ is a removable bottom portion having 70 a handle G². G³ is a second somewhat similar removable bottom portion having a handle G⁴ and a cut-away portion G⁵ to permit it to pass about the union B².

H is a vibrating element. In the form 75 here shown it is a steam hammer. Steam is applied to it through the connection H¹. It is fastened to the coil by means of the hanger H². The details of the hammer form no part of the present invention and are 80 therefore not shown. For the purpose of the present invention it is sufficient that a vibrating element be provided and the hammer serves this purpose. Any other vibrating element which would vibrate the coil 85 or the drier as a whole would serve the purpose and it would be within the contemplation of my present invention.

Although I have shown an operative device, still it will be obvious that many 90 changes might be made in size, shape and arrangement of parts without departing materially from the spirit of my invention; and I wish, therefore, that my showing be taken as in a sense diagrammatic.

Where the expression stationary is used, it is intended to convey the idea that the conveyor is not movably mounted, but is mounted in a fixed position, preferably being permanently fastened to a foundation 100

or other support. The vibratory mechanism which is applied to vibrate the device causes motion of the device, but does not move the device as a whole away from its position.

5 The use and operation of my invention are as follows:

The heater is normally mounted within a building or shelter and is preferably supported from above. Steam is turned into 10 it and it is made hot. Sand to be dried is poured into the open flaring top of the heater and passes down in contact with the coils. In the usual practice the sand will be put in until the heater is substantially 15 full, and as it runs out other sand will be put in, making the heater operate in a substantially continuous process. The sand will be heated by contact with the coil proper and with the interior heating element. The 20 heater is vibrated by operation of the steam hammer and thus the heating elements with which the sand is in contact are in a state of vibration and the sand is to some extent agitated and stirred up and lumps are thus 25 broken up and the sand is separated and shaken and is in effect stirred so that substantially all the sand comes in contact with the heating element.

As the sand is broken up it becomes small 30 enough to flow through the cracks between the pipes of the coil and it passes outward and is discharged from the drier and received in any suitable receptacle and conveyed away. The vibrating hammer serves 35 to expedite the flow of sand through and out of the drier, in addition to its function above described of tending to break up the sand and bring it in contact with the heating elements.

40 In order to permit removal of accumulated material such as dirt and other impurities, the removable bottom plates have been provided. When such material accumulates 45 these plates may be removed from bottom of the drier and the large particles discharged from the bottom, or in case they are too large to be discharged through the open bottom, they may of course be either broken up by tools through the open bottom or removed through the top of the drier. Usually when the bottom slides are to be removed, the drier is emptied of sand as 50 nearly as possible before making the removal.

55 I claim:

1. In a combined drier and sifter, a container formed to provide relatively limited 60 passages for the escape of material from within the container, a portion of said container forming a heating element and vibrating means for vibrating such heating element.

2. In a combined drier and sifter, a drying and sifting element forming a stationary

receptacle and provided with relatively limited 65 openings adapted to permit discharge of material therethrough from within the receptacle, an interior heating element and means for vibrating the drier.

3. In a combined drier and sifter, a drying and sifting element forming a stationary receptacle provided with relatively limited 70 openings adapted to permit discharge of material therethrough from within said receptacle, the said receptacle provided with 75 a removable bottom closure, an interior heating element and means for vibrating the drier receptacle.

4. In a combined drier and sifter, a main heating element forming in itself a substantially complete container and shaped to provide 80 relatively limited openings for the escape of material from within said container and an interior heating element in communication with said main element and 85 heated with it from a common source.

5. In a combined drier and sifter, a main heating element forming in itself a substantially complete container and shaped to provide 90 relatively limited openings for the escape of material from within said container and an interior heating element in communication with said main element and 95 heated with it from a common source, and means for vibrating such drier.

6. In a combined drier and sifter, a main heating element forming in itself a substantially complete stationary container and shaped to provide 100 relatively limited openings for the escape of material from within said container and an interior heating element in communication with said main element and heated with it from the same source and means for vibrating such drier, such 105 vibrating means being mounted directly on the heating element which forms the container.

7. In a combined drier and sifter, a heating element forming in itself a substantially complete stationary container and shaped to provide 110 relatively limited openings for the discharge of material therethrough from within said container, said container having flat sloping sides which converge toward the bottom and an additional interior heating 115 element in communication with the first mentioned element and heated with it from a common source.

8. In combination in a drying and sifting device, a heating element forming a stationary container shaped to provide relatively limited 120 openings for the escape of material from within the container and adapted to be supported from a fixed base, a portion of said heating element shaped to form a 125 partition within said container, the partition and the container forming a part of the same heating system, and means attached

to said container for causing the same to vibrate within itself while held upon a fixed base.

9. In combination in a heating and sifting device, a heating element forming a stationary container and so shaped as to provide relatively limited passages for the escape of the material from the container, and means

attached to the container for causing the same to vibrate within itself while mounted on a fixed base.

Signed at Chicago, county of Cook and State of Illinois, this 9th day of December, 1925.

CLYDE P. ROSS.
